REFRIGERATOR CAR CONSTRUCTION

Charles E. Crede, Chicago, Ill., assignor to Standard Railway Devices Company, a corporation of Delaware

Application January 13, 1940, Serial No. 313,674

7 Claims. (Cl. 108—5.6)

This invention relates to refrigerator cars used to transport perishable commodities at a predetermined temperature. The essential features of a refrigerator car are an insulated body to prevent or retard ingress of heat during warm weather and egress of heat during cold weather and a cooling means and a heating means to be used during warm and cold weather respectively.

This invention applies particularly to cars in which the cooling means, preferably containers for water ice, eutectic ice, brine or dry ice, are disposed immediately below the roof of the car. The lading is supported in spaced relation to the floor by a foraminous rack. Flues, preferably associated with the side walls of the car, communicate between the cooling means and the space under the floor rack to provide a path for the circulation of air. The path is from the cooling means downwardly through the aforementioned flues, through the space under the floor rack, upwardly through the lading compartment thereby cooling the lading, and finally to the cooling means from where the cycle is repeated.

The refrigerant containers in a car of this type are commonly arranged with a row thereof adjacent each side wall and a space extending longitudinally of the car at the center thereof between the rows of containers. The containers are also preferably spaced apart longitudinally of the car so that carlines may extend between the containers and be secured to the opposite side walls of the car.

An object of the invention is to provide a strong, light and easily made carline which not only provides an adequate support for the containers, but also is provided with means to permit circulating air to come in contact with the ends of the container thereby contributing to the efficiency of the refrigeration.

The refrigerant container commonly used in a car of this type has end walls made pan shaped with the flanges thereof projecting outwardly. Another object of the invention is to provide a carline well adapted to use with this kind of refrigerant container.

A further object of the invention is the provision of a carline which may be easily attached to the side wall of the car as well as to the refrigerant container.

Other objects and advantages of my invention will be apparent from the following detailed description by referring to the accompanying drawings.

In the drawings:

Fig 1 is a perspective view of a portion of a refrigerator car showing a portion of a side wall, the end portions of two adjacent refrigerant containers and a part of the carline.

Fig. 2 is a longitudinal vertical sectional view through the carlines and refrigerant containers shown in Fig. 1. The section is taken on line 2—2 of Fig. 3.

Fig. 3 is a plan view of a portion of the structure shown in Fig. 1.

Fig. 4 is an exploded view of the attachment of the carline to a side wall of the car.

Fig. 5 shows a modified form of carline.

Figs. 6, 7 and 8 are similar to Fig. 2 but show modified forms of carline and attachment of the carline to the refrigerant container.

Fig. 9 is a section on line 9—9 of Fig. 3.

Fig. 10 shows a modified structure which may be used in place of the structure shown in Fig. 9.

In the type of refrigerator car shown in the drawings the wall 2 is comprised of an outer sheathing 4; an inner post 6; a flue sheet 8; a lining 10 and insulation 12 between the flue sheet 8 and the sheathing 4. The flue sheet 8 has outwardly projecting panels 14 formed therein to provide flues 16 between the panels 14 and the lining 10 for flow of refrigerated air.

The refrigerant containers 18 preferably have the bottom 19 and side walls 20 formed integral and the top 22 formed of a separate piece 24 and secured to the bottom part by bolts 26. The end walls 27 are preferably pan shaped with the flanges 28 projecting outwardly in flatwise relation with the bottom 19, side walls 20 and top 22 30 of the container 18 and secured thereto. A hatch 30 is preferably provided in the top 22 of each container 18 for the loading of refrigerant.

In the form of my invention shown in Fig. 1, a carline 36 is comprised of a substantially vertical plate 37 which extends substantially between the opposite side walls 2 of the car. The upper and lower marginal portions of the plate 37 are slit preferably vertically to a considerable distance from the upper and lower edges of the plate. The parts of the plate between the slits are bent laterally, preferably in alternate directions and inclined, to form flanges 39, 40. The flanges 39, 40 preferably have horizontal edge portions 41, 42 which are secured to the upper and lower parts respectively of the refrigerant container 18. In the modification shown in Figs. 1 and 2 the upper edge portions 41 are disposed above the top 22 of the container 18 and the lower edge portions 42 above the outwardly projecting flanges 28 of the 50 end walls 27. This arrangement facilitates the 55

removal of any refrigerant container without disturbing the others, which removal may be accomplished by removal of the bolts 44.

In the modification shown in Fig. 6 the flanges 39, 40 of the carline 36 project inside the flanges 28 of the end walls 27 and are secured thereto, preferably by the rivets 45. This arrangement provides greater strength than that heretofore described, but is undesirable from an assembly standpoint, inasmuch as one refrigerator container cannot be removed without disturbing the others.

Fig. 7 is similar to Fig. 6 except for the elimination of the rivets 45 and the substitution of welding 48 therefor.

In Fig. 8 the carline flanges 39, 40 are secured directly to the end walls 27 of the containers instead of to the flanges 28 thereof or to the tops 22 or bottoms 19 of the containers.

The end portions of the carline plate 37 are 20 preferably formed with the flanges 54, 55 horizontal and oppositely projecting so as to form in combination with the web 51 a Z-shape. Separate angle pieces 59, 60 having horizontal legs 63, 64 are secured to the end portions of the plate 37 projecting oppositely from the flanges 54, 55 to form an I-section, as shown in Fig. 4. Brackets 67 for supporting the carline 36 are secured to the inner posts 6, as shown in Fig. 4. Each bracket 67 comprises a substantially vertical web 68 and spaced apart horizontal flanges 70, 71, the webs 68 of the brackets 67 being spaced apart for the insertion of the vertical web 51 of the carline 36. The upper (54) and lower (55) flanges of the plate 37, as well as the legs 63, 64 35 of the angle pieces 59, 60, secured thereto, rest upon and may be secured to the flanges 70, 71 of the brackets 67, thereby supporting the carline 36.

As shown in Fig. 3, there are refrigerant containers 18 adjacent each side wall 2 and a space 75 between the containers 18 at the center of the car. This space 75 between the containers is preferably spanned by diaphragm pieces 77 in substantial alignment with the end walls 27 of the containers 18 and may be secured to the containers. The upper (39) and lower (40) flanges of the carline 36 are secured to the diaphragm 77, as shown in Fig. 9, to reinforce the carline 36 at the center thereof. Apertures 79 are provided in the diaphragm 77 for circulation of air near the carline 36.

Fig. 10 shows a modified construction in which the diaphragm 82 is substantially horizontal and also acts to reinforce the carline 36 at the center thereof.

Since a refrigerator car of this type usually has a row of refrigerant containers 18 near each wall 2, the containers brace 18 themselves by reason of the carlines 36 interposed therebetween against longitudinal movement and the structure shown in Fig. 1 therefore provides a very strong support for the containers 18. Means may be provided to prevent the movement of one container relative to another, such as the straps 85, 86 shown in Figs 6 and 7, which extend between and are secured to the adjacent end portions of adjacent containers. Such a construction provides a strong girder type carline having a vertically disposed web 81, an upper chord comprising the laterally disposed flanges 39 and the straps 85 and a bottom chord comprising laterally disposed flanges 40 and the lower straps 86.

Fig. 5 shows a modified form of carline 36 in which slots 90 are provided between the laterally

projecting flanges 91 instead of slits, as shown in the carline of Fig. 1. An arrangement, such as shown in Fig. 5, provides greater opportunity for air flow between the ends of adjacent containers.

The accompanying drawings illustrate the preferred form of the invention, though it is to be understood that the invention is not limited to the exact details of construction shown and described, as it is obvious that various modifications thereof, within the scope of the claims, will occur to persons skilled in the art.

I claim:

1. Means to support a plurality of refrigerant containers including a carline supported at its opposite ends by spaced apart walls of a refrigerator car and disposed between a pair of said refrigerant containers, said carline having oppositely projecting upper and lower flanges extending outwardly therefrom and secured to said containers.

2. Means to support a plurality of refrigerant containers including a carline supported at its opposite ends by spaced apart walls of a refrigerator car and disposed between a pair of said refrigerant containers, said carline comprising a substantially vertical plate having the upper and lower marginal portions thereof slit, the parts of said plate between said slits being bent laterally to form flanges secured to said containers.

3. Means to support a plurality of refrigerant containers including a carline supported at its opposite ends by spaced apart walls of a refrigerator car and disposed between a pair of said refrigerant containers, said carline comprising a substantially vertical plate having the upper and lower marginal portions thereof slit, the parts of said plate between said slits being bent laterally on alternate sides of said plate to form flanges secured to said containers.

4. Means to support a plurality of refrigerant containers including a carline supported at its opposite ends by spaced apart walls of a refrigerator car and disposed between a pair of said refrigerant containers, said carline comprising a substantially vertical plate having the upper and lower marginal portions thereof slit, the parts of said plate between said slits being bent laterally to form flanges secured to said containers, each upper flange projecting on the opposite side of said plate from the lower flange aligned vertically therewith.

5. Means to support a plurality of refrigerant containers including a carline supported at its opposite ends by spaced apart walls of a refrigerator car and disposed between a pair of said refrigerant containers, said carline comprising a substantially vertical plate having the upper and lower marginal portions thereof slit, the parts of said plate between said slits being bent laterally to form flanges secured to said containers, the upper and lower flanges being inclined upwardly and downwardly, respectively, from said plate and members extending between and secured to said containers adjacent certain of said flanges.

6. Means to support a plurality of refrigerant containers including a carline supported at its opposite ends by spaced apart walls of a refrigerator car and disposed between a pair of said refrigerant containers, the adjacent ends of said containers comprising substantially vertical walls having outstanding peripheral margins, said carline comprising a substantially vertical plate having the upper and lower marginal portions thereof slit, the parts of said plate between said slits

being bent laterally to form flanges secured to said margins.

7. Means to support a plurality of refrigerant containers including a carline supported at its opposite ends by spaced apart walls of a refrigerator car and disposed between a pair of said refrigerant containers, said carline having oppositely projecting upper and lower flanges ex-

tending outwardly therefrom and secured to said containers, the upper and lower flanges being inclined upwardly and downwardly, respectively, from said carline, and members extending between and secured to said containers adjacent certain of said flanges.

CHARLES E. CREDE.
